United States Patent Office

Des. 188,906
Patented Sept. 27, 1960

188,906

KITE

Dionisio P. Gorospe, 2305 Chester St. SE.,
Washington, D.C.

Original application June 4, 1959, Ser. No. 56,201. Di-
vided and this application Mar. 23, 1960, Ser. No.
60,322

Term of patent 14 years

(Cl. D34—15)

FIG. 1.

FIG. 2.

FIG. 3.

Figure 1 is a top plan view of a kite showing my new design;

Figure 2 is a bottom plan view thereof; and

Figure 3 is a side elevational view thereof.

This application is a division of my application, Serial No. D. 56,201, filed June 4, 1959.

I claim:

The ornamental design for a kite, as shown and de-
scribed.
